[57] **CLAIM**

The ornamental design for an air compressor, substantially as shown and described.

DESCRIPTION

FIG. 1 is a perspective view of an air compressor showing my new design;

FIG. 2 is an elevational view thereof showing the side opposite that in FIG. 1;

FIG. 3 is a front elevational view thereof;

FIG. 4 is a rear elevational view thereof;

FIG. 5 is a top plan view thereof.

The design resides in the portions shown in full lines in the drawing, the underside of the design being without ornamentation.

FIG. 1

FIG. 3

FIG. 2

FIG. 4

FIG. 5
